UNITED STATES PATENT OFFICE.

JOHN SCHEFFER, OF NEWARK, NEW JERSEY.

STOVE BOARD.

1,427,023.

Specification of Letters Patent. Patented Aug. 22, 1922.

Application filed June 22, 1920. Serial No. 390,784.

To all whom it may concern:

Be it known that I, JOHN SCHEFFER, a citizen of the United States, residing at Newark, in the county of Essex and State of New Jersey, have invented new and useful Improvements in Stove Boards, of which the following is a specification.

This invention relates to a supporting board for a stove for protecting the floor from the heat and the principal object of the invention is to provide a board of neat and attractive appearance and one which can be easily cleaned by washing or the like.

Another object of the invention is to construct the board in such a manner that it is prevented from warping by inserting reinforcing strips in the base under the metal surface and to provide a border for covering the edges of the metal.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a plan view of one form of the invention.

Figure 2 is a section on line 2—2 of Figure 1.

Figure 3 is a view on line 3—3 of Figure 1.

Figure 4 is a view of another form.

Figure 5 is a section on line 5—5 of Figure 4.

Referring to Figures 1, 2 and 3, 1 indicates the base board which is rabbeted at its edges, as shown at 2. The face of the board is provided with the grooves 3, to receive the metal reinforcing strips 4. A metal plate 5 is placed on the board and this plate is held

in place by the ornamental frame 6, which has a portion engaging the rabbeted part of the base board, and an edge engaging the edge of the plate. This frame is secured to the base board by screws or the like, driven through the under face of the board and engaging said frame. The metal plate rests upon the upper part of the reinforcing strips and these strips prevent warping of the board by the heat. The plate may be enamelled and provided with suitable designs to add to the attractiveness of the device.

It is thought from the foregoing description that the advantages and novel features of the invention will be readily apparent.

I desire it to be understood that I may make changes in the construction and in the combination and arrangement of the several parts, provided that such changes fall within the scope of the appended claims.

Having thus described my invention, what I claim as new and desire to protect by Letters Patent is:

1. A stove board of the class described comprising a base board having its edges rabbeted and grooves formed in its upper face, reinforcing strips arranged within said grooves, a metal plate arranged on said board, an ornamental frame having a portion engaging the rabbeted part of the board and an edge engaging the edge of the plate.

2. A stove board of the class described comprising a base board having its edges rabbeted and grooves formed in its upper face, metal reinforcing strips arranged within said grooves, an enamelled plate resting on said board and a border frame held in the rabbeted part of the edge overlapping the plate for holding the same in place, said enamelled plate resting upon the upper part of the reinforcing strips thereby preventing the warping of the board.

In testimony whereof I affix my signature.

JOHN SCHEFFER.
